UNITED STATES PATENT OFFICE.

HARRY C. WEISKITTEL, OF BALTIMORE, MARYLAND, ASSIGNOR TO A. WEISKITTEL & SON CO., OF BALTIMORE, MARYLAND, A CORPORATION OF DELAWARE.

BATHTUB.

Application filed September 22, 1925. Serial No. 57,878.

To all whom it may concern:

Be it known that I, HARRY C. WEISKITTEL, a citizen of the United States, residing at Baltimore, State of Maryland, have invented certain new and useful Improvements in Bathtubs, of which the following is a description, reference being had to the accompanying drawing and to the figures of reference marked thereon.

This invention relates to new and useful improvements in bath tubs, and more particularly to a cast iron bath tub having a porcelain enameled coating.

An object of the invention is to provide a cast iron bath tub with a hollow rim, which rim is closed throughout its entire length, but open at an end whereby the core used in the casting of the rim can be removed.

A further object of the invention is to provide a bath tub of the above character with integral wall flanges for filling in the space between the tub and the wall, both at the top and at the end or side thereof.

A further object of the invention is to provide a bath tub of the above character wherein the hollow rim along the edge of the tub extends across the wall flanges and is formed integral therewith.

These and other objects will in part be obvious and will in part be hereinafter more fully disclosed.

In the drawings which show by way of illustration one embodiment of the invention—

Figure 1 is a plan view of a bath tub embodying my improvements, said tube being constructed so as to extend from one side wall of the bath room to the other side wall thereof;

Figure 1^a is a plan view of a slightly modified form;

Fig. 2 is an end view of the tub shown in Fig. 1;

Fig. 3 is a side view of a portion of the tub shown in Fig. 1, and

Fig. 4 is a sectional view on the line 4—4 of Fig. 1.

The invention is directed broadly to a cast metal bath tub, and preferably a cast iron tub. The tub is provided with a hollow cast rim which is formed integral with the tub and cast at the same time the tub is cast. This hollow rim extends along one side of the tub, and when the tub is used in the corner of a room it extends around and

across the end of the tub. The walls of the hollow rim are of substantially the same thickness as the wall of the tub, and the wall on the under side of the rim extends around and is cast integral with the wall 60 of the tub. At each end of the tub there is a wall flange when the tub is built in and extends from one wall of the bath room to the other, and also a side flange for the back of the tub. When, however, the tub 65 is used in the corner of a room, then there is only a wall flange at one end and one side of the tub. This hollow rim along the side or end of the tub extends clear to the wall and is formed integral with the wall 70 flange.

The invention will possibly be better understood by a detail description of the embodiment of the invention set forth in the accompanying drawings.

The bath tub is indicated at 1 and is of the usual construction as far as the bottom, side and end walls are concerned, until the upper portion of the tub is reached. In Fig. 1 of the drawings, I have shown a cast 80 iron tub adapted to be used in a bath room for the built in tub. This tub extends from one side wall of the room to the other. The tub is provided with a hollow rim 2 along the front side thereof. This hollow rim is shown in cross section in Fig. 4 of the drawings, and consists of a top member 3, an upper member 4 and an underneath member 5. It is noted that the walls of these three members as well as the side walls of the tub 90 indicated in Fig. 4, are all of substantially the same thickness. The underneath member 5 of the rim is carried around and is formed integral with the side wall 6 at 7. There is a curved fillet which joins the member 5 and the side wall of the tub. This rim is hollow, and the hollow space is indicated at 8 in this figure. I am aware that cast iron bath tubs have been heretofore manufactured with a rolled rim, but this rolled rim is open on 100 the under side, and this, of course, results in an edge on the rim which is more or less rough, and thus objectionable. In my present hollow rim there is no exposed rough edge, and the tub with its hollow rim closely 105 resembles a solid porcelain tub. The hollow rim is not only a great advantage in that it avoids this rough edge which is formed on the usual cast iron tub, but it is also very light as compared with a rim.

formed of solid metal, but more than this, this hollow rim throughout the entire extent thereof, is of substantially the same thickness, and this enables a porcelain enamel coating to be applied to the entire tub, inasmuch as the metal being of the same thickness can be uniformly heated. At the rear side of the tub, there is a short wall flange 9 which is adapted to contact with the wall of the bath room. In the form of the invention shown in Fig. 1, there is an end wall flange 10 at one end of the tub, and the end wall flange 11 at the other end of the tub. This is for a built in tub, where the tub extends from one side wall to the other of the bath room. The rim 2 extends the full length of the tub and the end walls 10 and 11, and this rim is formed integral with the vertical floor flanges 12, 12 which extend from the wall flange to the floor. This floor flange 12 is back from the front edge of the tub, and the under member 5 of the hollow rim is carried under still farther so as to be formed integral with the floor flange at the point 13. Here again, there is a curved fillet which causes the entire tub to resemble a solid porcelain tub.

In Fig. 2 I have shown an end view of the tub, and it will be clear from this view that this hollow rim extends to the extreme edge of the wall flange 11. The core used in the casting of the tub can be readily removed through the open end of the cast rim, or through both ends of the cast rim. In Fig. 1^a of the drawings, where I have shown a tub adapted to fit in the corner of a room, the hollow rim 2 along the side of the tub extends around and across the end of the tub as indicated at 14. There is, of course, a floor flange 15 at the back side of the tub, and the floor flange 12 at the front side of the tub. In this case the hollow rim is open at the ends adjacent the wall flanges so that the core may be readily removed. The tub is, of course, provided with the usual supporting base flange, 15.

From the above description, it will be apparent that I have provided a cast iron tub which is very light in construction, and wherein the rim along the exposed side and end of the tub is hollow and is closed. The rim is a relatively wide rim without being over deep. This is due to the fact that the core can be used of any desired cross sectional area in the forming of the rim, and this core is not circular. Thus it is that the rim may be given the same appearance as used in connection with a solid porcelain tub. Furthermore, both the walls of the tub and the walls of the rim may have a porcelain enameled coating applied thereto, so that the entire tub has the appearance of a solid porcelain tub.

It is obvious that minor changes in the

details of construction and the arrangement 65 of the parts may be made without departing from the spirit of the invention as set forth in the appended claims.

Having thus described the invention, what I claim as new and desire to secure by Letters-Patent, is—

1. A cast metal bath tub having a hollow rim along one side thereof, said rim having the under face thereof extended around to and formed integral with the side wall of 75 the tub, so that said rim is closed intermediate the ends thereof, said rim at least one end thereof being open so that the core utilized in the casting of the rim can be readily removed.

2. A cast metal bath tub having an integral hollow rim along the side thereof and an integral end flange at the end of the tub, said hollow rim being extended to the full width of the wall flange and formed integral therewith, said rim being open at its end and closed throughout the length thereof.

3. A cast metal bath tub having an integral hollow rim along the side thereof and an integral end flange at the end of the tub, said hollow rim being extended to the full width of the wall flange and formed integral therewith, said rim being open at its end and closed throughout the length thereof, the thickness of the metal forming the hollow rim being substantially the same as the thickness of the metal forming the tub, whereby the entire cast tub can be coated with porcelain enamel.

4. A cast metal tub having a hollow rim extending along one side thereof, a horizontal wall flange along the end of the tub, and a vertical floor flange extending from the horizontal flange to the floor, said wall flange and said floor flange being formed integral with the tub, and said hollow rim extending across both the end flange and floor flange and formed integral therewith, said rim being open at its ends and closed throughout the length thereof.

5. A cast metal bath tub having a hollow rim extending along one side thereof, a horizontal wall flange along the end of the tub, and a vertical floor flange extending from the horizontal flange to the floor, said wall flange and said floor flange being formed integral with the tub and said hollow rim extending across both the end flange and floor flange and formed integral therewith, said rim being open at its ends and closed throughout the length thereof, the walls of said hollow rim and the wall of the floor flange and the end flange being of substantially the same thickness as the wall of the tub.

In testimony wherof, I affix my signature.

HARRY C. WEISKITTEL,
